UNITED STATES PATENT OFFICE.

ARTHUR H. BROWN, OF HAMILTON, MISSOURI.

CROWN AND BRIDGE WORK.

No. 818,661.

Specification of Letters Patent.

Patented April 24, 1906.

Application filed September 18, 1905. Serial No. 278,907.

To all whom it may concern:

Be it known that I, ARTHUR H. BROWN, a citizen of the United States, residing at Hamilton, in the county of Caldwell and State of Missouri, have invented a new and useful Improvement in Crown and Bridge Work, of which the following is a specification.

This invention relates to crown and bridge work.

10 The object of the invention is materially to improve upon existing modes of constructing crowns and bridges whereby practically all strain will be removed from the anchoring-pins, resulting thereby in the production of 15 work having greater stability and capable of producing higher artistic effect.

With the above and other objects in view, as will appear as the nature of the invention is better understood, the same consists in the 20 novel manner of constructing crowns and bridges, as will be hereinafter fully described and claimed.

In the accompanying drawings, forming a part of this specification, and in which like 25 characters of reference indicate corresponding parts, Figure 1 is a view in vertical section through an incisor constructed in accordance with the present invention. Fig. 2 is a perspective view of the same. Fig. 3 is a view 30 in side elevation, exhibiting the retainer combined with the tooth. Fig. 4 is a view in vertical longitudinal section through a bicuspid constructed in accordance with the present invention. Fig. 5 is a view in perspective of 35 the bicuspid shown in Fig. 4, exhibiting the construction of its lingual surface. Fig. 6 is a view in perspective, showing a bicuspid with a cap and dowel combined therewith and constructed in accordance with the present 40 invention. Fig. 7 is a view in perspective of a retainer used in carrying the procedure into effect. Fig. 8 is a view in perspective of a denture, taken from the front and constructed in accordance with the present invention. 45 Fig. 9 is a similar view taken from the rear of the denture shown in Fig. 8.

The tooth of the present invention has as much or more porcelain in it as the ordinary vulcanite tooth and has also headed pins to 50 be used in crown and bridge work. It is, however, distinctly different from the ordinary vulcanite tooth and to such an extent that it could not be very successfully used as a vulcanite tooth, while a vulcanite tooth 55 could not be substituted for the present invention, inasmuch as the pins of necessity

would have to be shorter and set well up under the shoulder, or what will hereinafter be termed the "pressure-receiving" surface.

In crowns or bridges in which facings are 60 used the metal backing must be allowed to cover the occluding surface of the facing to insure it against breakage, and this necessitates an undesirable display of gold and, further, increases the expense of the operation 65 by requiring a large amount of gold. The procedure of the present invention eliminates visible gold and reduces the amount required, thereby lessening both the expense and the work and time of construction. Furthermore, 70 it renders unnecessary the subjection of the tooth to the heat necessary to effect soldering, whereby the danger of fracturing the tooth or of changing its color is eliminated. Further, by having the thin incisal third of 75 each of the anterior teeth devoid of metal backing there is secured a life-like translucent appearance that has heretofore been exceedingly difficult to obtain. Furthermore, in the present invention the stress or pressure 80 is resisted by a novel pressure-receiving surface or shoulder on the tooth, this being true of the incisors and cuspids, while the posterior teeth have two of the pressure-receiving surfaces as bases, leaving the pins simply to 85 retain the tooth in this position. The tooth is therefore stronger from the fact that there is a greater bulk of porcelain and is of more spherical form.

Another feature of a bridge constructed in 90 accordance with the present invention is that the lingual surface, by virtue of the retainer, which preserves the natural form of the tooth, presents a broad smooth surface exposed to the tongue.

The features of novelty that define this invention from the art are, first, the teeth being 95 more bulky are stronger, and the fact that in all the teeth the stress is received by a pressure-receiving surface and in the posterior teeth by two pressure-receiving surfaces makes the liability of fracture very remote; second, the ease, facility, and cheapness with 100 which a crown or bridge may be made; third, the teeth are removed while soldering is being 105 effected, thereby eliminating all danger of cracking or of changing the color of the teeth, and as no drying out of the investment is necessary, as with facings, the case may be 110 quickly heated and instantly cooled, thereby materially shortening the operation; fourth, in a finished crown or bridge the incisal edge

of the tooth shows no gold and has life-like translucency, adding thereby greatly to the appearance of the teeth; fifth, in case of breakage another tooth may be fitted and the repair completed immediately and without pain or annoyance.

Referring to the drawings and to Figs. 1, 2, and 3, 1 designates an incisor the lingual surface of which is provided with a shoulder 2, constituting a pressure-receiving surface, which is disposed approximately at right angles to the length of the tooth and adjacent to which are disposed two anchoring-pins 3, that are preferably parallel with the shoulder and exactly at right angles to the flat lingual surface 4. The gold-retainer 5 (shown in detail in Fig. 7) is provided with two open-sided sockets 6, which are adapted to be engaged by the headed pins 3 and bears 20 squarely against the shoulder, whereby the latter is caused to receive all of the pressure, the pins merely serving to hold the retainer and tooth assembled. As usual, the retainer is held combined with the pins by cement that 25 excludes moisture and insures firmness.

In the form of the invention exhibited in Figs. 4, 5, and 6, wherein the pins are shown applied to a bicupid, the latter is provided with two shoulders 7 and 8, the former being disposed at right angles to the length of the tooth and the latter obliquely with relation thereto. The shoulder 7 is engaged by the retainer 5, as above described, and the shoulder 8 by a portion of the base of the cap 9, as 35 shown in Fig. 6, the retainer and cap, as usual, being soldered together.

In the form of the invention shown in Figs. 8 and 9 the manner in which the bridge is constructed is exhibited, the bridged teeth 10 being soldered, as usual, to the two crowns 11, carrying dowels or anchoring-posts 12. In this form of the invention the manner of assembling the retainer with the teeth is the same as that described, the only difference 45 being that bridgework is shown instead of mere crownwork, as in Fig. 6. In order to strengthen the suspension 13, iridio-platinum wire 14 may be soldered to the bridge.

While the procedures above described are 50 confined to bicuspids, it is to be understood that they are equally adaptable for use in connection with molars, and as this will be apparent detailed illustration is omitted.

In constructing a crown according to the 55 present invention the cap and dowel or cope are first made in the same manner as for a Richmond crown. An impression is then taken, the model poured, and the tooth selected. To the gingival surface of the retainer is soldered with twenty-carat solder a piece of pure-gold plate of thirty-six gage, that is large enough to extend under the crown and to protrude at the gingivo-labial or gingivo-buccal angle, and is adapted to 60 any inequalities at the back of the tooth and

is allowed to overlap the tooth slightly at the mesial and distal aspects. The retainer, with backing, is then placed in position on the tooth and waxed in position on the coping, no wax being allowed to adhere to the tooth, but only to the retainer and backing. The tooth is then removed and the case invested, soldered, and then finished and is finally cemented in position. In the case of a bridge-tooth the same method of soldering a 75 gold plate to the retainer is observed, except that it need not extend under the tooth only so far as it is desired to have the solder flow. After the completion of the case the tooth is cemented in position in the manner described. 80

It will be seen from the foregoing description that when stress or pressure is applied to a tooth or denture constructed in accordance with the present invention it will be in the direction of the length or long diameter of the 85 tooth and will thus be transmitted directly to the shoulder or shoulders, whereby danger of straining or breaking the anchoring-pins is removed, and a more effective resistance to displacement is secured. 90

Having thus described the invention, what is claimed is—

1. A denture embodying a retainer provided in one edge with sockets disposed wholly within it, and a tooth having a shoulder to engage the retainer and close the sockets and headed pins to engage the sockets. 95

2. A denture embodying a tooth provided with a flat pressure-receiving shoulder disposed approximately at right angles to its 100 length and extending throughout the width of the tooth and with headed anchoring-pins extending parallel with the shoulder, and a retainer to be engaged by the shoulder and provided with sockets to be engaged by the 105 headed ends of the pins.

3. A denture comprising a tooth having its lingual surface provided with two flat shoulders arranged in step order, one of which is disposed at right angles to the length of the tooth and the other obliquely thereto, a headed retainer engaging one of the shoulders, and means for assembling the tooth and retainer. 110

4. A denture comprising a tooth having its 115 lingual surface provided with two flat shoulders arranged in step order, one of which is disposed at right angles to the length of the tooth and the other obliquely thereto; a headed retainer engaging the first-named 120 shoulder, and means for assembling the tooth and the retainer.

In testimony that I claim the foregoing as my own I have hereto affixed my signature in the presence of two witnesses:

ARTHUR H. BROWN.
